DISPENSING CONTAINER WITH FLEXIBLE WALLS

Arthur P. Corella, 8166 Vanscoy Ave., North Hollywood,
Calif., and William S. Schneider, 1765 Rohr Ave.,
Glendale, Calif.

Filed Mar. 2, 1964, Ser. No. 78,837

Term of patent 14 years

(Cl. D58—2)

FIG. 1 is a perspective view of a dispensing container with flexible walls, showing our new design.

FIG. 2 is an elevational view thereof showing the side opposite to that shown in FIG. 1.

FIG. 3 is an end elevational view thereof taken from the left of FIG. 2.

FIG. 4 is an end elevational view thereof taken from the right of FIG. 2.

FIG. 5 is a top plan view thereof.

FIG. 6 is a bottom plan view thereof.

We claim:

The ornamental design for a dispensing container with flexible walls, as shown.
